PHYSIOLOGICAL-PARAMETER-WAVEFORM DISPLAY SCOPE

David P. Chuboff, North Barrington, and James P. Stevens, Chicago, Ill., assignors to Zenith Radio Corporation, Chicago, Ill., a corporation of Delaware

Filed Feb. 26, 1969, Ser. No. 15,931

Term of patent 14 years

Int. Cl. D24—02

U.S. Cl. D83—1

The figure is a left side top and front perspective view of our design for a physiological-parameter-waveform display scope.

The right side (not shown) is the same as the left side shown, and the rear and bottom surfaces are plain and unornamented.

We claim:

The ornamental design for a physiological-parameter-waveform display scope, as shown and described.
